UNITED STATES PATENT OFFICE

CLAYTON E. WYRICK, OF DETROIT, MICHIGAN, ASSIGNOR TO GAIRING TOOL COMPANY, OF DETROIT, MICHIGAN, A CORPORATION OF MICHIGAN

FLOATING REAMER

Application filed November 2, 1928. Serial No. 316,719.

My invention relates to reamers and more particularly to a driving mechanism for floating reamers.

One object of my invention is to provide a reamer having a universally movable driving connection between the reamer and a holder supported in a suitable chuck, the driving force of the universal connection being applied to the reamer in advance, or substantially 10 near the forward end of the tool, adjacent that portion of the reamer carrying the maximum load of the cutting operation, with the reamer blades trailing in the path of the bore of the work in order that the tool may 15 align itself with the bore regardless of whether the machine spindle or holder is or is not in axial alignment with the hole to be reamed.

Another feature of the invention is the 20 universal driving connection between the reamer and the holder, consisting of a suitable shaft provided at each end with a polygonal-shaped driving head or nose, respectively extending into a substantially complementary shaped socket at the forward end of the reamer, and at the rear end into a similarly shaped socket in the holder, thereby providing a double universal joint, permitting the tool to follow through holes on a true 25 line with the axis of the hole regardless of the load.

A further object of the invention is to provide a reamer with a pilot on its forward end and universal driving means as described to 30 permit said reamer to trail said pilot through the bore.

With the foregoing and other objects in view which will appear as the description 35 proceeds, the invention further resides in the combination and arrangement of parts and in the details of construction hereinafter described and claimed, it being understood that changes may be made in the precise embodiment of the invention shown without departing from the spirit of the same.

In the drawings accompanying this specification:

Figure 1 is a side elevation of the tool supported in a holder and chuck, showing the

reamer as it would appear in the work, with parts broken away and in section.

Figure 2 is a cross-sectional view taken on or about line 2—2 of Figure 1.

Figure 3 is a fragmentary elevation and 55 longitudinal sectional view through the reamer, showing the polygonal-shaped head of the driving connection seated in a like shaped socket at the forward end of the reamer.

Figure 4 is a cross-sectional view taken on or about line 4—4 of Figure 1, showing an 60 end elevation of the holder.

Figure 5 is a side elevation of an inserted 65 blade reamer and holder, with parts broken away and in section.

Figure 6 is a semi-elevation and cross-sectional view through the reamer shown in Figure 5, with the end thrust cap removed to disclose the polygonal-shaped driving socket 70 and the correspondingly shaped head of the driving connection in position.

In floating reamers it has been customary 75 to drive the reamer by means engaging the rear portion of the tool body, and as a result there is a tendency to restrict the movement of the reamer so that it cannot float freely with reference to the driving member.

The present invention is designed to overcome these objections to the prior art by providing a driving connection having a double universal movement and wherein the driving force is applied substantially adjacent or preceding the forward end of the cutting blades; or the maximum working load as 85 applied to the blades.

As a result of the driving force being applied at this point augmented by a lead pilot, the rear portion of the reamer follows the forward cutting edges, or the lead set by 90 the pilot, and this floating trailing action is adhered to throughout the reaming operation.

In the prior art referred to the force applied to the reamer was a pushing force which in many instances resulted in causing the tool to cut a tapered or bell mouthed hole and urged a departure of the axis of the reamer from the axis of the work and especially 95 was this true if the holder of the reamer 100

was not in true alignment with the hole to be reamed.

In the present invention the driving force is substantially a pulling force guided by a pilot and the blades of the reamer trail in the path formed by the bore on their forward cutting ends—adjacent to or preceding which the driving force is applied to the tool.

10 Referring now to the letters of reference placed upon the drawings:

A denotes a reamer, and A^a a pilot which is preferably integral and extends forward of the cutting blades B.

15 C denotes an arc-shaped polygonal socket at the forward end of the reamer body and D a thrust cap or plug screwed into the reamer, closing the opening beyond the socket. E is a disc inserted adjacent the cap.

20 F indicates a shaft, extending through a relatively larger bore in the reamer body and at its forward end is formed with an arc-shaped polygonal driving head or nose F^a,—fitting into the complementary socket C,—with the arc-shaped end bearing against the disc E, held in position by the thrust cap.

The shaft F fits loosely in the bore of the reamer in order that the reamer may adapt 30 itself to any variation occurring between the axis of the holder and the bore of the work, and at the rear end is provided with an arc-shaped polygonal head F^b, fitted to a corresponding socket G^a in the tool holder G, in turn supported in a chuck H.

I denotes a set screw extending through the wall of the holder into a peripheral groove in the shaft F adjacent the hexagonal head at the rear end of the shaft.

40 J indicates an L-shaped member, adjustably supported at the end of the tool holder by a set screw K extending into the body of the holder, having beveled edges J^a slideable in a correspondingly beveled guide G^b provided at the end of the holder G.

The member J has a V-shaped notch in that portion of the plate overlapping the end of the tool holder, which upon adjusting the set screw K is designed to limit the 50 downward sag of the shaft F, to support the reamer when free from the work.

Figures 5 and 6 show a reamer fitted with interchangeable cutting blades B^a, provided with a double universal driving connection 55 similar to that previously described, and it should be noted that the portion of the inserted blade B^b is circle-ground which substantially serves as one form of pilot for this type of reamer.

60 Having thus described my invention what I claim is:

1. In a tool of the character described, a reamer body portion, fitted with cutter blades and constructed with a central longitudinal bore, including a polygonal shaped socket at

its forward end; means for closing the end of said socket; and a driving connection, comprising a shaft extending loosely through the bore, having an arc-shaped polygonal driving head, fitted to the polygonal shaped socket in the reamer body portion, whereby said reamer body portion, including its cutter blades located back of the polygonal shaped driving socket, are adapted to follow the driving force applied to the reamer body.

2. In a tool of the character described, a reamer body portion fitted with a plurality of cutting blades, having a central longitudinal bore with a polygonal shaped socket at its forward end; means for closing the end of said socket; holding means provided with a polygonal socket; a driving connection comprising a relatively short shaft extending through the bore in the reamer body portion, having an arc-shaped polygonal head at each end respectively fitted to the sockets in the holding means, and in the reamer body portion whereby the body of the reamer may float under torsional load, said reamer including its cutter blades being located back of the polygonal shaped socket in the reamer body portion, that the cutting blades may follow the driving force applied to the reamer body portion through the driving connection.

3. In a tool of the character described, a reamer body portion having a central longitudinal bore with a polygonal shaped socket at its forward end; means for closing the end of said socket; a tool holder provided with a polygonal socket; a driving connection comprising a relatively short shaft extending through the bore in the reamer body, having an arc-shaped polygonal head at each end respectively fitted to the sockets in the tool holder and body of the reamer, thereby permitting the body of the reamer to float under torsional load; and a plurality of removable cutter blades supported in grooves extending rearwardly from the polygonal shaped socket in the reamer body portion, whereby the cutting blades are adapted to follow the driving force applied to the reamer body portion through the driving connection.

4. In a tool of the character described, a reamer body portion having a central longitudinal bore with a polygonal shaped socket at its forward end; means for closing the end of said socket; a tool holder provided with a polygonal socket; a driving connection comprising a relatively short shaft extending through the bore in the reamer body, having an arc-shaped polygonal head at each end respectively fitted to the sockets in the holder and body of the reamer, thereby permitting the body of the reamer to float under torsional load; a set screw supported in said tool holder having a projecting end extending into a peripheral groove in the shaft of the driving connection; and an adjustable

forked member located at the end of the tool holder for supporting the driving connection upon the withdrawal of the reamer body from the work, said reamer body including cutter blades located back of the polygonal shaped driving socket in the body, whereby the cutting blades are adapted to follow the driving force applied to the reamer body through the driving connection.

10 In testimony whereof, I sign this specification.

CLAYTON E. WYRICK.
